UNITED STATES PATENT OFFICE

149,117

DESIGN FOR A TRANSPARENT
PAPERWEIGHT

John G. Funfrock, Morgantown, W. Va.

Application February 25, 1947, Serial No. 137,160

Term of patent 7 years

(Cl. D74—12)

To all whom it may concern:

Be it known that I, John G. Funfrock, a citizen of the United States, and residing at Morgantown, in the county of Monongalia and State of West Virginia, have invented a new, original, and ornamental Design for a Transparent Paperweight, of which the following is a specification, reference being had to the accompanying drawing, forming a part thereof.

In the drawing,

Figure 1 is a plan view of a transparent paperweight, showing my new design;

Figure 2 is a perspective view of the transparent paperweight shown in Figure 1; and

Figure 3 is a sectional view along the broken plane indicated by the line III—III of Figure 1.

My design for a transparent paperweight is characterized by the specific elements of ornamentation within the weight and the particular placement of the same.

I claim:

The ornamental design for a transparent paperweight, substantially as shown and described.

JOHN G. FUNFROCK.
